UNITED STATES PATENT OFFICE.

ALBERT J. GURNEY, OF CANTON, OHIO, ASSIGNOR TO THE AMERICAN MINE DOOR CO.,
OF CANTON, OHIO, A CORPORATION OF OHIO.

RELAY.

Application filed May 19, 1926. Serial No. 110,259.

This invention relates to an improved relay and while being well adapted for more or less general use is, nevertheless, particularly designed to be employed in connection with safety signalling systems for mines, electric railway systems, or the like, and seeks, among other objects, to provide a device comprising an assembly of simple pieces of apparatus but which shall be certain of operation in the desired manner under all circumstances and free from objectionable arcing at the contacts or overheating in the coils.

A further object of the invention is to provide an improved device embodying a primary switch for completing a circuit through either coil of the relay and wherein, when the relay switch is swung in either one direction or the other by reason of the energization of one of said coils, as the case may be, the primary switch will be automatically swung for breaking the circuit through the coil energized so that after the coil has functioned, no potential will exist across the terminals of said coils or can be unintentionally applied across said terminals to cause overheating of the coils.

A further object of the invention is to provide a device wherein, when one coil, for instance, is energized and the relay switch is swung in one direction, the primary switch will be swung to complete a circuit through the other coil, and vice versa, so that the latter coil may be subsequently energized for swinging the relay switch in the opposite direction.

And the invention seeks, as a still further object, to provide a device wherein a circuit will be closed through either coil but momentarily at any one time so that the coils may be designed to have sufficient pull even at very low voltages.

Other objects of the invention not specifically mentioned in the foregoing will appear during the course of the following description.

In the accompanying drawings:

Figure 1 is a front elevation of my improved relay, the door of the casing of the device being shown open.

Figure 2 is a vertical sectional view on the line 2—2 of Figure 1, looking in the direction indicated by the arrows.

Figure 3 is a fragmentary sectional view on the line 3—3 of Figure 2, looking in the direction indicated by the arrows.

Figure 4 is a sectional view on the line 4—4 of Figure 1, looking in the direction indicated by the arrows.

Figure 5 is a detail perspective view particularly showing the switch blades.

Figure 6 is a diagrammatic view showing the circuit connections.

In carrying the invention into effect, 1 employ a preferably metal casing or box 10 normally closed by a door 11, and mounted upon the side walls of the casing near the 65 lower end thereof are insulators 12 through which suitable leads may be arranged to extend into the casing. Fixed to the bottom wall of the casing is a pair of spaced vertically disposed metal brackets 13 having base 70 flanges 14 bolted or otherwise secured to said bottom wall, and formed on said brackets at their upper ends, as particularly seen in Figure 2, are upstanding ears 14'. The brackets are widened toward the upper ends thereof, 75 and projecting between the brackets are side flanges 15 to which are riveted or otherwise fixed a pair of angle plates 16. Mounted upon said angle plates are electro-magnets, indicated for convenience of description at 80 17 and 18, and bearing against the upper ends of the coils of said magnets are keeper plates 19 fixed to the angle plates 16. As will be observed, the magnets are tilted laterally, 85 due to the widening of the brackets 13.

Mounted to rock on the brackets 13 is a switch lever 20 comprising a U-shaped yoke which straddles the ears 14' of the brackets, and extending through the side members of said yoke and through said ears is a pivot 90 pin 21 pivotally connecting the yoke with the brackets. The yoke is preferably shaped from suitable resilient sheet metal, and fixed to the side members of the yoke near the inner ends thereof is a pair of transversely extending metal strips or arms 22 offset toward each other at opposite sides of the yoke. Fixed between the ends of said strips are armatures 23 and 24 disposed to cooperate with the magnets 17 and 18 respectively. Bolted or otherwise secured to the outer end of the yoke is an insulating block 25, and fixed to said

block is a flexible resilient switch blade 26. As seen in Figure 5, this switch blade is preferably composed of a pair of companion metal strips or blade members bent at their inner ends to overlie the side faces of the block, and extending through said members and through the block is a bolt 27 rigidly connecting said members with the block. Near their outer ends the blade members are formed with oppositely bowed portions 28 which abut at the outer terminal of the blade and serve to space the outer end portions of the blade members apart so that the blade may readily flex.

Bolted or otherwise fixed to the top wall of the casing is an insulating block 29, and mounted upon said block are spaced angle shaped contact holders 30 and 31 secured to the block, as seen in Figure 1, by terminals 32 and 33, the holders 30 and 31 being identical in construction. The base wings of the holders 30 and 31 are provided at their outer ends with lugs 34 which are received in suitable sockets in the block 29 for locking the holders against rotation on the terminals 32 and 33, and extending from the depending wings of said holders are flanges 35. Yieldably gripped by said flanges are preferably carbon contacts 36 and 37 confronting each other in parallel relation and, as will be observed, the switch blade 26 projects between said contacts for cooperation at its free end therewith. The sides of the contacts are beveled while the corresponding flanges at the sides of the depending wings of the holders are inclined to coact with the beveled sides of said contacts so that the contacts will be securely fixed upon the holders. However, by removing the holders from the block 29, the contacts may be readily slipped from between said flanges and removed, when new contacts may be substituted in lieu thereof.

Mounted upon the outer side member of the yoke of the switch lever 20 is an arm 38 which is pivotally connected with said side member by a rivet or other suitable fastening device 39 and projects upwardly beyond the yoke over the switch blade 26. At its upper end, the arm is bent outwardly to form an ear 40 while near its lower end the arm is provided with a slot 41, and extending through said slot and through the outer side member of the yoke is a bolt 42 securing the arm against pivotal movement on the yoke. Extending through the bottom wall of the casing 10 in a vertical plane with the pivot pin 21 of the switch lever is an anchoring device 43, and secured at one end to said anchoring device is a spring 44 having a straight elongated end portion 45 engaged with the ear 40 of the arm 38.

As will now be seen, when a circuit is closed through the magnet 18, the armature 24 will be attracted by said magnet for rocking the switch lever 20 to the right, as seen in Figure 1, and moving the switch blade 26 into engagement with the contact 37. Similarly, when a circuit is closed through the magnet 17, the armature 23 will be attracted for rocking the switch lever to the left and moving the switch blade into engagement with the contact 36. As the switch lever travels toward the right, the spring 44 will, as soon as the ear 40 of the arm 38 crosses the vertical plane of the pivot pin 21 of the switch lever, accelerate the movement of the lever and snap the switch blade against the contact 37, when the spring will function to prevent accidental rocking movement of the switch lever away from the contact and hold the switch blade in engagement therewith. Similarly, as the switch lever travels toward the left, the spring 44, will, as soon as the ear 40 of the arm 38 crosses the vertical plane of the pivot pin 21 of the switch lever, immediately function to accelerate the movement of the lever and snap the switch blade into engagement with the contact 36, when the spring will serve to prevent accidental rocking movement of the switch lever away from said contact and hold the switch blade in engagement therewith. Thus, in effect, the spring 44 provides a means for yieldably locking the switch lever in either one position or the other when swung to close a circuit through the contact 36 or close a circuit through the contact 37, as the case may be. Furthermore, as will be seen, the arm 38 may be adjustably swung on the pivot 39 and secured in adjusted position by the bolt 42 for varying the disposition of the free end of the arm relative to the pivot pin 21 of the switch lever, so that, if desired, the spring may be caused to exert a greater locking pressure on the lever when swung in one direction than when swung in the other direction.

Bolted or otherwise secured to the back wall of the casing is a transversely extending insulating strip 46 lying in a plane touching the upper face of the block 25 of the switch lever, and mounted on said strip is a terminal 47 to which, as will be later explained, a wire is connected for electrically grounding said terminal. Extending between said terminal and the bolt 27 which secures the switch blade 26 is a conductor 48 electrically connecting the switch blade with said terminal. Accordingly, when the switch lever is swung to engage the switch blade with the contact 36, a circuit will be closed through the terminal 32, through said contact, and through the switch blade to the grounded terminal 47. Similarly, when the switch blade is swung to engage the contact 37, as shown in Figure 1, a circuit will be closed through the terminal 33, through said contact, and through the switch blade to the grounded terminal 47.

Mounted to swing upon the insulating strip 46 is a primary switch blade 49 on the lower end portion of which are formed lateral ears 130

50, and extending through said ears is a pivot pin 51, the inner end of which is received in a suitable socket in the strip 46. Extending through the strip and through the inner end 5 of said pin is a key 52 locking the pin against displacement, and attention is now directed to the fact that said pin is located in a vertical plane with the pivot pin 21 of the switch lever 20 and with the anchoring device 43 of the 10 spring 44. Formed in the switch blade 49 is an opening 53 and engaged at one end through said opening is a spring 54, the opposite end of which is anchored to a pin or other fastening device 55 sunk into the inner end of the 15 insulating block 25 of the switch lever 20, as seen in Figure 3, medially of said block. Thus, the spring provides a yieldable connection between said switch lever 26 and the switch blade 49. Mounted upon the insulating 20 block 29 for engagement by the switch blade 49, when swung in one direction, is a pair of resilient contact members 56, and mounted upon said block for engagement by the switch blade, when swung in the opposite direction, 25 is a pair of similar resilient contact members 57. As best shown in Figure 3, these several contact members are all angle shaped, the free end portions thereof being bent to define upwardly presented spring tongues 58, and 30 bracing said members are angle shaped reinforcing plates 59 provided at their outer ends with lugs 60 which are received in suitable sockets in the block 29 for locking the reinforcing plates against turning movement. 35 Connecting the pair of contact members 56 with the block 29 are terminals 61 and 62, and connecting the pair of contact members 57 with said block are terminals 63 and 64. These terminals are countersunk in the insulating block and extend through the contact 40 members as well as through the reinforcing plates 59 for rigidly securing these parts to said block. As will be observed, the spring tongues 58 of the contact members are adapted 45 to yield under the pressure of the switch blade 49 when engaged thereby and will accordingly compensate for any looseness which may develop in the mounting of the switch blade to always provide efficient electrical 50 contact between the switch blade and said contact members.

In Figure 6 of the drawings, I have shown the circuit connections employed within the casing as well as typical circuit connections 55 which may be employed externally of the casing. Leading from the terminal 62 to one end of the coil of the magnet 18 is a wire 65 and leading from the other end of said coil to the terminal 47 is a wire 66, while a wire 60 67 is connected to the terminal 47 for electrically grounding the latter terminal. Leading from the terminal 64 to one end of the coil of the magnet 17 is a wire 68, and connecting the other end of said coil with the 65 terminal 47 is a wire 69. As previously

noted, the wire 48 connects the switch blade 26 with said terminal. Connected with the terminal 61 is a line circuit 70 in which is interposed a suitable switch or like device 71, and connected with the terminal 63 is a line circuit 70 72 in which is interposed a suitable switch or like device 73. In the present instance, I have shown an annunciator circuit 74 connected with the terminal 32 and a similar annunciator circuit 75 connected with the terminal 33.

Assuming now that the parts are in the position shown in Figure 1, it will be seen that the annunciator circuit 75 is closed through the contact 37, switch blade 26, conductor 48, 80 and wire 67 so that the annunciator in the circuit 75 is energized. Furthermore, the line circuit 72 is closed across the terminals 63 and 64 by the engagement of the switch blade 49 with the contact members 57. Accordingly, 85 when the switch 73 is closed, current will flow in the line circuit 72 across said terminals through the switch blade 49 to the wire 68, thence through the coil of the magnet 17 and through the wire 69, and thence through the wire 67 to ground. Thus, the magnet 17 will, 90 as previously described, be energized for rocking the switch lever 20 to the left, as seen in Figure 1, and moving the switch blade 26 into engagement with the contact member 36. 95 The annunciator circuit 75 will therefore be broken while the annunciator circuit 74 will be closed through the switch blade 26, the wire 48, and the wire 67 to ground, so that the annunciator in the circuit 74 is energized. 100

Attention is now directed to the fact that due to the yieldable connection provided by the spring 54 between the switch lever 20 and the switch blade 49, the switch blade 49 will, during the initial portion of the travel of the switch lever, remain closed in engagement with the contact members 57 so that the circuit through the magnet 17 will be maintained closed by the switch blade. Accordingly, said magnet will remain energized to 105 effect the rocking movement of the switch lever until the switch lever has crossed the pivotal center thereof, the spring 54 stretching as the swinging movement of the switch lever progresses. However, after the pin 55 110 has crossed the vertical plane of the pivot pin 51 of the switch blade 49 to approach the end of its throw and the switch lever is being swung to the end of its movement by the spring 44, as previously described, the spring 54 will function to swing the switch blade 49 out of engagement with the contact members 57 and into engagement with the contact members 56 for breaking the circuit through the magnet 17 and closing a circuit across the 115 contact members 56. Thus, as will be perceived, the circuit through the magnet 17 will not be broken to extinguish the pull of the magnet 17 on the armature 23 until after the lever 20 has crossed its pivotal center and is 120 125 130

being swung by the action of the spring 44 so that said spring will not only act on the switch lever to complete the travel thereof but will also provide the impetus for snapping 5 the switch blade 49 out of engagement with one pair of contacts and into engagement with the other pair of contacts.

Assuming the switch lever 20 and switch blade 49 to be swung to the left, it will be seen 10 that when the switch 71 is closed, current will flow in the circuit 70 across the terminals 61 and 62 through the switch blade 49, and thence through the wire 65, the magnet 18, the wire 66, and the wire 67 to ground. Accordingly, 15 the magnet 18 will be energized for attracting the armature 24 and swinging the switch lever 20 to the right so that the switch blade 26 will be moved into engagement with the contact 37 for closing the annunciator 20 circuit 75. During the initial portion of the travel of the switch lever, the switch blade 49 will remain in engagement with the contact member 66 so that the magnet 18 will remain energized until the switch lever has crossed 25 the pivotal center thereof when, as the lever approaches the end of its throw and the movement of the lever is continued by the spring 44, the switch blade 49 will be swung by the spring 54 out of engagement with the contact members 56 and snapped into engagement with the contact members 57, the parts functioning in the same manner when the switch lever is swung to the right as when the switch lever is swung to the left, as previously described.

Having thus described the invention, what I claim is:

1. A relay including spaced brackets, a switch lever including a yoke pivoted upon 40 said brackets, arms carried by the yoke, armatures carried by said arms, electromagnets mounted upon the brackets to cooperate with said armatures for swinging the lever alternately in opposite directions, a switch blade carried by the lever, a switch contact mounted for engagement by said blade, contact members electrically connected with said magnets, a pivoted switch blade movable to engage said contact members alternately 50 and close a circuit through said magnets alternately, and a spring forming a connection between the lever and the pivoted blade for swinging the pivoted blade by the lever.

2. A relay including spaced brackets, a switch lever including a yoke pivoted upon 55 said brackets, arms carried by the yoke, armatures carried by said arms, electromagnets mounted upon the brackets to cooperate with said armatures for swinging the lever alternately in opposite directions, a switch blade carried by the lever, a switch contact mounted for engagement by said blade, contact members electrically connected with said magnets, a pivoted switch blade movable to 60 engage said contact members alternately and

close a circuit through said magnets alternately, a spring forming a connection between the lever and the pivoted blade for swinging the pivoted blade by the lever, and a spring connected with the lever for swinging the lever to the end of its throw when rocked in either one direction or the other and holding the lever at the end of its throw.

3. A relay including a pivoted switch lever, electromagnets for swinging the lever in opposite directions, a switch blade carried by the lever, a switch contact mounted for engagement by the blade, spaced pairs of contact members having spring tongues, certain of said members being electrically connected 80 with said magnets, a pivoted switch blade movable alternately in opposite directions to engage the tongues of said pairs of switch members for closing a circuit through said magnets alternately, and a connection between the lever and the pivoted switch blade for swinging the pivoted blade by the lever.

4. Circuit closing means comprising a pivoted switch lever, a spring associated with 90 the switch lever to automatically and positively move it in each direction after receiving an initial movement to carry it past a neutral or dead line, a switch blade, and a spring connection between the switch lever 95 and the switch blade to throw the latter simultaneously with the switch lever as it moves under the influence of the spring associated therewith.

5. Circuit closing means comprising a pivoted switch lever, an arm carried by the switch lever and adjustable laterally with reference thereto, a spring connected to said arm and exerting a pull thereon to throw the switch lever when initially moved from a neutral position to the right or left, a switch blade and a spring connection between the switch lever and the switch blade to throw the latter simultaneously with the switch lever as it moves under the influence of the 100 spring connected with the laterally adjustable arm.

6. Circuit closing means comprising a pivoted switch lever, an arm pivoted to the switch lever, means for pivotally adjusting the arm and securing it in the required adjusted position, a spring connected to the arm and exerting a pull thereon to throw the switch lever when initially moved to the right or left from a neutral position, a switch blade, and a spring connection between the switch lever and the switch blade to throw the latter simultaneously with the switch lever as it moves under the influence of the spring connected with the laterally adjustable arm.

7. Circuit closing means comprising a pivoted switch lever, a circuit closing blade carried by the switch lever and insulated therefrom, an arm adjustably connected with the switch lever, a spring connection with the 125

arm and exerting a pull thereon to throw the switch lever when initially moved to the right or left from a neutral position, electromagnets for initially moving the switch lever in each direction, a switch blade for controlling the circuits through the electromagnets, and a spring connection between the switch lever

and the last mentioned switch blade to throw the latter simultaneously with the switch lever as it moves under the influence of the ¹⁰ spring connected with the adjustable arm.

In testimony whereof I affix my signature.

ALBERT J. GURNEY. [L. S.]
